CLAIM

The ornamental design for a suspension bracket, as shown and described.

DESCRIPTION

FIG. 1 is a rear perspective view of a suspension bracket showing our new design;

FIG. 2 is a front elevational view thereof;

FIG. 3 is a side elevational view of the right-hand side thereof, the left-hand side view being a mirror image of FIG. 3; and

FIG. 4 is a rear elevational view thereof;

FIG. 5 is a top plan view thereof; and,

FIG. 6 is a bottom plan view of our new design for a suspension bracket.
